CLAIM

The ornamental design for a work table, as shown and described.

DESCRIPTION

FIG. 1 is a perspective view of a work table showing my new design;

FIG. 2 is a left side elevational view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a left side elevational view with the table top in a raised, horizontal position;

FIG. 8 is a left side elevational view with the table top in a raised, tilted position; and

FIG. 9 is a perspective view of an alternative embodiment of the work table of FIG. 1.
